UNITED STATES PATENT OFFICE.

LOUIS I. WEED, OF CLIPPER MILLS, CALIFORNIA.

CAN AND FAUCET FOR SAME.

1,070,864.

Specification of Letters Patent. Patented Aug. 19, 1913.

Application filed June 4, 1912. Serial No. 701,681.

To all whom it may concern:

Be it known that I, LOUIS I. WEED, a citizen of the United States, residing at Clipper Mills, in the county of Butte and State 5 of California, have invented new and useful Improvements in Cans and Faucets for Same, of which the following is a specification.

This invention relates to cans and faucets 10 for the same, the primary object of the invention being to provide a can embodying a depressed cup in the top thereof, in conjunction with a faucet detachably mounted in a socket in the bottom of the cup, and 15 adapted, when detached, to be housed entirely within said cup, so as to offer no projection beyond the natural confines of the can.

A further object of the invention is to 20 provide in connection with such cup a carrying handle for the can, which is adapted to fold within the plane of the cup, so as to offer no projection which is liable to become broken or injured.

By means of the construction hereinafter 25 described, cans may be equipped with faucets and carrying handles which are capable of being housed entirely within the lines of the can, so as to offer no projection whatever, thereby adding greatly to the portability and compactness of the can, adapting a large number of cans to be stored or packed 30 in a comparatively small space, while preserving the integrity and usefulness of the 35 faucet and the carrying handle.

With the above and other objects in view, the invention consists in the construction, combination and arrangement of parts, as will be hereinafter more fully described, 40 illustrated in the accompanying drawings, and pointed out in the claims hereunto appended.

In the drawings: Figure 1 is a plan view of a can, embodying the present invention. 45 Fig. 2 is a vertical section through the upper portion of the can, showing the faucet and handle housed therein. Fig. 3 is an enlarged vertical section through the upper portion of the can, showing the cup, the faucet, the 50 socket therefor, and the carrying handle. Fig. 4 is a vertical section through the cup, showing the manner of connecting the han-

die thereto. Fig. 5 is a plan view of the handle *per se*. Fig. 6 is a plan view, showing a slightly different arrangement of faucet and socket therefor.

Referring to the drawings, 1 designates an ordinary liquid dispensing vessel in the form of a square or rectangular can, having the flat parallel sides, and flat top and bottom.

In carrying out this invention, I provide a cup 2 which is located in the top of the can, said cup being depressed entirely below the plane of the top of the can, so as to provide a flush top for the can, above which there is no projection whatever. This enables a number of cans to be piled one upon another, without any loss of space. In the preferred embodiment of this invention, the 70 cup 2, which is rectangular in shape, is constructed of sheet metal, and preferably stamped or pressed up from a single blank, so as to comprise the four vertical sides 3, the bottom 4, and a top flange 5 located at 75 the top of the body of the cup, which flange is adapted to be soldered or otherwise permanently secured and sealed to the top of the can, which is of course formed with an opening to receive said cup. It is, however, 80 possible to form said cup as an integral part of the can top proper by depressing a portion of said top, preferably adjacent to one corner, at which point it is desirable to locate the faucet, hereinafter described, so as 85 to facilitate pouring off the contents of the can.

In the bottom of the cup 2, there is arranged an internally threaded socket 6 adapted to receive the threaded neck of the 90 faucet, hereinafter described. This socket is closed at the bottom by an imperforate bottom wall 7, which is adapted, however, to be punctured by any suitable instrument, when it becomes necessary to pour off the contents 95 of the can which, up to the time of puncturing the bottom 7, remain hermetically sealed in the can. The socket 6 is provided at the top thereof with a flange 8 adapting the same to be securely fastened, as by solder, 100 to the bottom wall of the cup 2, the socket extending down below the plane of the bottom of the cup, as clearly shown in the drawings.

In connection with the threaded socket 6, I employ a detachable faucet which comprises a cylindrical body 9, a reduced and threaded neck 10 adapted to screw into the socket 6, and a valve seat 11, located at the junction of the body and neck, the parts 9, 10 and 11 being preferably formed of a single piece of sheet metal, which is pressed into the exact shape required, to form the body, the reduced neck and the valve seat. This provides a construction of the smallest possible size, and to that extent reduces the necessary size of the cup 2, in which the faucet is housed, when not in use.

15 Extending outwardly from the lower portion of the body line is a spout 12, which it will be seen communicates with the faucet body immediately adjacent to the valve seat 11, so that the liquid does not have to pass by the valve, but finds its way outward under the valve and directly through and from the spout 12. At its top, the body 9 is closed by a cap 13 which is provided with a central threaded hole 14, through which 20 passes a threaded and adjustable valve stem 15, provided at its outer end with a handle 16, by means of which said stem may be turned. At its inner end, said stem carries 25 a valve body 17, preferably of leather, rubber, or some such soft, flexible material, the same being backed up by a metal disk 18, to which the stem 15 is connected, preferably by a loose or swivel joint, so as to enable 30 the valve to rock and accommodate itself 35 perfectly to the valve seat 11, thereby effectively sealing the can and preventing any leakage.

It will be seen from the foregoing description, that the liquid passing outward 40 through the faucet does not need to get past the valve 17, and this avoids leakage through the hole 14, through which the valve stem passes. Furthermore, when the valve 17 is screwed down tightly against 45 its seat, the can is effectively sealed, and there can be no loss or leakage therefrom. Furthermore, in the case of volatile liquids, the strength of the liquid is not impaired through evaporation.

50 19 designates a carrying handle which is of quadrilateral form, and comprises a pair of spring terminals 20 which are set slightly out of parallelism with the opposite side of the handle. These terminals are received in 55 a sleeve 21 located within the plane of the cup 2, as shown, and it will now be understood that in view of the fact that the spring terminals are not arranged in parallel planes, they will bind within said sleeve, and thereby securely hold the handle at any 60 angle to which the same may be adjusted. In this way the handle not only acts as a carrying means for the can, but also as a

retaining means for the faucet, when the latter is inscrewed from the socket and laid 65 down in the cup, in the manner illustrated in Figs. 1 and 2. Thus all parts, including the faucet and the carrying handle, are included entirely within the plane of the outer surface or confines of the can in connection 70 with which said parts are employed. Until the bottom of the cup is punctured, the can is hermetically sealed, thereby thoroughly protecting the contents thereof. Furthermore, the faucet is always carried by the 75 can, thereby avoiding any danger of loss of the faucet.

Instead of providing the socket in the bottom of the depressed cup, as hereinabove described, the depressed cup may be arranged 80 in the center of the top of the can, as illustrated in Fig. 6, and the socket for the faucet may be arranged in one corner of the top of the can, as illustrated in the same view. This has the advantage of locating 85 the carrying handle in the center of the can, while at the same time providing means for connecting the faucet to the corner of the can, so that the entire contents thereof may be easily poured out.

90 What is claimed is:

1. A can, embodying a depressed cup in the top thereof having an imperforate bottom, a threaded socket in the bottom of said cup and extending downward below the bottom of the cup, a faucet adapted to be screwed into the socket and also adapted when unscrewed from the socket to be housed wholly within the plane of the cup, and a bail-shaped faucet retaining device attached to the can within said cup and adapted to be folded wholly within the plane of said cup, said device also forming a carrying handle for the can.

2. A can, embodying a depressed cup in the top thereof having an imperforate bottom, a threaded socket in the bottom of said cup and extending downward below the bottom of the cup, a faucet adapted to be screwed into the socket and also adapted when unscrewed from the socket to be housed wholly within the plane of the cup, and a bail-shaped faucet retaining device attached to the can within said cup and adapted to be folded wholly within the plane of said cup, said device also forming a carrying handle for the can, and embodying spring terminals extending normally at an angle to each other, and a sleeve in said cup in which said terminals are forcibly held in line with each other.

3. An attachment for cans, consisting of a cup having an imperforate bottom, a threaded socket in the bottom of said cup extending downwardly below the bottom of the cup, a faucet adapted to be screwed into the socket

and also adapted when unscrewed from the
socket to be housed wholly within the plane
of the cup, and a bail-shaped faucet re-
taining device attached to the cup and
adapted to be folded wholly within the
plane of said cup, said device also forming a
carrying handle.

In testimony whereof I affix my signature
in presence of two witnesses.

LOUIS I. WEED.
